STRUCTURE FOR LETTERING SCRIBERS

Gunnar B. Hansen, 1143 Sunnyside Ave., and Frank L. Johnson, 1129 East 4th South, both of Salt Lake City, Utah

Filed Aug. 12, 1963, Ser. No. 301,556
2 Claims. (Cl. 120—98)

The present invention relates to lettering scribes, and, more particularly, to certain improvement structure for lettering scribes wherein the popular drawing pens currently used in ruling pen contexts may be employed in scribe apparatus and, hence, enable the user to duplicate line weight in all parts of a particular drawing where desired, for example.

Lettering equipment currently used in mechanical drawing and in other contexts includes a lettering scribe in combination with one of a plurality of templates of various types. The scribe is used for duplicating characters on the template, and these characters may be letters, numbers, electrical symbols, and so forth.

The lettering scribes above referred to generally come in lettering sets which include a plural number of scribe pens of various sizes which give varying line weights (i.e. thicknesses). In conventional practice a draftsman or artist is supplied with a lettering scribe set (including scribe, a set of pen points for the scribe, and a plural number of desired templates); he is also supplied with a set of fountain pen type, mechanical drawing pens which operate on a plunger principle and are now quite generally used in preference to the old-fashioned ruling pens. These presently preferred mechanical pens have proven very suitable for fast line work. Many of these pens are manufactured in Germany and are sold under the trademark "Rapid-O-Graph" and "Korinoor." Such pens have caps and include threaded portions on their barrels for receiving the pens' caps. It would of course be desirable to use the same drawing pens for scribe work in order to eliminate the need for separate scribe inking points and also to insure that line weights of scribed portions of the drawing and general line work thereof is identical.

Now different types of mechanical drawing pens, while including caps threaded onto the pen barrels, nonetheless vary in dimension and in outer contour and, furthermore, the threaded portions thereof may be proximate or quite remote from the pen point.

Accordingly, it is a principal object of the present invention to adapt conventional scribe equipment for employment of mechanical drawing pens of the plunger type wherein the threaded portions of the pen barrels may be utilized to facilitate mounting of the pen to a lettering scribe.

Another object is to provide new and useful scribe structure.

A further object of the invention is to provide for adjustability in the vertical orientation of a mechanical drawing pen when the same is included in modified scribe structure designed to accommodate such pens.

A further object of the invention is to provide in a lettering scribe a writing tool holder which will accommodate either one or a number of different types of mechanical drawing pens.

A further object of the invention is to provide a scribe wherein the identical pens used for drawing purposes may also be employed for lettering, numbering, symbols schematic designations, and so forth.

A further object is to provide adjustable slot means in a writing tool holder for lettering scribes which may facilitate pen placement as the same is inserted into a scribe holder preparatory to usage of the scribe.

A further object is to provide a versatile attachment for conventional scribe apparatus, which attachment

2

serves as a holder of one of a selected number of drawing pens.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings in which:

FIGURE 1 is a perspective, exploded view of conventional scribe apparatus in combination with the scribe attachment of the present invention; this attachment shall hereinafter be referred to as a writing tool holder, and this whether the same is an integral part of or is releasably affixed to the scribe apparatus.

FIGURE 2 is a side elevation of the writing tool holder shown in FIGURE 1 exploded away from the scribe proper.

FIGURE 3 is a fragmentary view, principally in section, and taken along the line 3—3 in FIGURE 2.

FIGURE 4 is an elevation, principally in vertical section, of the writing tool holder of FIGURE 2 wherein the same includes an adapter ring dimensioned to receive a mechanical drawing pen the barrel of which is threaded for engagement with the adapter ring.

FIGURE 5 is an enlarged detail of the top portion of the writing tool holder, with the adapter ring, of FIGURE 4.

FIGURE 6 is a top plan of the structure shown in FIGURE 4, is fragmentary in nature, and also illustrates the mounting of the writing tool holder attachment to the scribe proper; for convenience of illustration the pen shown in FIGURE 4 is not shown in FIGURE 6.

FIGURE 7 is a side elevation similar to FIGURE 4, is partially sectioned, but illustrates the writing tool holder as incorporating a new adapter ring designed to receive another type of mechanical drawing pen.

In FIGURE 1 lettering scribe 10 is shown to include conventional scribe parts comprising scribe frame 11, tail pin 12 releasably secured thereto, and adjustable arm 13 adjustably secured by knurled thumb screw 14 to scribe frame 11, the adjustable arm 13 having scribe point 15. In conventional practice, the arm 13 is made movable or adjustable about the axis of thumb screw 14 so that lettering slant may be pre-determined as desired. Scribe frame 11 includes a front extension 16 provided with vertically oriented apertures 17 and 18 which contiguous with the longitudinal slit 19, the latter being selectively constricted by the conventional thumb screw 20 provided. In practice, thumb screw 20 is threaded through the aligned, threaded apertures 21 provided in the forward extension 16. Also preferably included in the lettering scribe design is a grasping boss 22' which is graspable by the thumb and fingers of the user and which is permissively removable from the scribe frame 11.

In normal practice the apertures 17 and 18 may be used, alternately, for receiving and retaining in place lettering tools commonly referred to as lettering points. Of course, conceivably but one aperture such as aperture 17 need only be provided. Fixed retention of the points is enabled through the provision of thumb screw 20.

The present invention contemplates the employment of a writing-tool holder 22 provided with pins 23 and 24 so dimensioned as to be adapted for pressed or other insertion into apertures 17 and 18 and retention therein by thumb screw 20. Where but one aperture, such as aperture 17, is supplied, then but one pin (23) need be required; however, in this case, if the writing-tool holder 22 is in fact supplied with two pins 23 and 24, then the same may be mounted into the aperture (17) provided for that purpose and the rearmost pin (24) of the writing-tool

holder simply disposed outside of and adjacent the forward extension 16 of the lettering scribe.

FIGURE 2 indicates in elevation the essential details of the basic writing-tool holder. The same is shown to include a hollow holder portion 25 and a mounting portion 26 integral therewith and provided with the aforementioned protruding pins 23 and 24 as shown in FIGURE 2. FIGURES 2 and 7 indicate that the writing-tool holder 22 is provided with respective pairs of mutually, vertically aligned slots 27 and 28. The slots shall be referred to as adjustment slots for purposes hereinafter set forth.

The mounting of writing-tool holder 22 to the lettering scribe 10 at scribe frame 11 thereof is best illustrated in FIGURE 3 wherein it is seen that thumb screw 20, in being threaded through the forward extension 16 of scribe frame 11, operates to releasably secure in a very convenient and yet positive manner the pins 23 and 24 of writing tool holder 22 into the forward extension 16.

FIGURES 4-6 are important and indicate adapter ring provision made to accommodate the writing-tool holder for writing tool inclusion. FIGURE 4 illustrates writing pen 29 as being retained within writing-tool holder 22 by provision of an adapter ring 30, the same being provided with outwardly extending threaded studs 31 and 32 which respectively receive washers 33, 34 and knurled nuts 35, 36. Writing pen 29 is supplied with threads 37 on its barrel exterior; thus, the adapter ring 30 is so dimensioned that its interior surface may be threaded at 38 to cooperate with threads 37 of pen 29.

It will be seen in FIGURE 4 that the slots 27 accommodate the up-and-down, slideable adjustment of threaded studs 31 and 32 in order that the pen point 40 of pen 29 be at a correct position for proper line production. If desired, an annular, C-configured spring 41 may be held under compression within the hollow holder portion 25 and thus frictionally and springingly engage the hollow holder portion 25. The same will serve as an adjustable stop abutment for adapter ring 30 so that readjustment of pen point level will not be required for each insertion of the pen 29.

Correspondingly, where a different type of pen (see pen 50 in FIGURE 7), though threaded, is to be inserted into the hollow holder portion 25, then a spring 42, similar to spring 41 in FIGURE 4, and a new adapter ring 43 will be provided. Adapter ring 43 in FIGURE 7 includes threaded studs 44 and 45 which cooperate with slots 28 so as to permit slideable adjustment of the adapter ring 43 within hollow holder portion 25. Again, spring 42 serves as an adjustable stop abutment. Washers 46 and nuts 47 serve as releasable securement means in order to position the adapter ring 43 in a proper manner.

The manner of operation of the device which is the subject of the present invention is as follows. Clearly, the writing-tool holder 22 is at the crux of the present invention, and it may be a separate part as shown in FIGURE 1, or, conceivably may be an integral part of a scribe unit. Where pens having threaded exteriors are to be used in conjunction with the basic scribe apparatus, then the writing tool holder will become a part of the lettering

scriber 10. Where one type of pen such as that shown at 29 in FIGURE 4 is to be employed, then its adapter ring 30 is selected and suitably positioned within hollow holder portion 25 by knurled nuts 35 such that proper point level is established. This may be accomplished simply by the user threading the adapter ring onto the pen and then positioning the adapter ring in the hollow holder portion 25 until the pen point (40) comes in contact with the paper. At this point the nuts 35 as retentive compression means are tightened down and the scribe is ready for use. A similar operation is involved in positioning a different type of pen and adapter ring (see FIGURE 7) in connection with the remaining slots 28. Thus, in practice the same holder 22, with appropriate adapter ring provision being made, can accommodate several different types of pens.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

We claim:

1. In a lettering scribe including a scribe frame, a tail pin affixed to and depending from a rearward portion of said scribe frame, and a scribe point affixed to said frame forwardly of said tail pin, an improvement comprising a writing tool holder affixed to said frame, said writing-tool holder comprising a hollow holder portion, and an interiorly threaded adapter ring cooperably disposed within said hollow holder portion and adapted to receive the threaded portion of a barrel of a mechanical drawing pen, and wherein said adapter ring is vertically adjustable within said hollow holder portion and wherein said structure includes means for releasably securing said adapter ring to and within said hollow holder portion at a desired position, and wherein said hollow holder portion of said writing tool holder was provided with vertical wall slots, said adapter ring being provided with threaded studs protruding outwardly through said slots, and nut means threaded upon said threaded studs for frictionally and compressingly securing said adapter ring to and within said hollow holder portion of said writing-tool holder.
2. Structure according to claim 1 wherein said hollow holder portion of said writing tool holder includes additional slot means for receiving alternate, interiorly threaded adapter ring means designed to threadedly engage another type of mechanical drawing pen.
